UNITED STATES PATENT OFFICE.

CALVIN I. KEPHART, OF PORTLAND, OREGON.

RIBBON GUIDE FOR TYPEWRITERS AND THE LIKE.

Application filed April 12, 1926. Serial No. 101,365.

This invention relates to an adjustable ribbon guide for the ink ribbon of type-writing machines, printing machines, and the like.

5 In many machines of this nature it is the usual practice to have the ink ribbon wound upon a spool or bobbin from which it is unwound onto a second spool, the ribbon between the two spools being threaded through 10 a suitable guide member which functions to maintain the ribbon in coincidence with the point at which the several type bars contact with the roller or printing platen. The ribbon, as thus mounted, is caused to pass constantly and progressively from one spool to 15 the other so that its entire length may be utilized as a source of ink supply. It is usual to employ a ribbon which is several times greater in width than the point of impact of the type bars, so that, in the absence 20 of some means to shift the path of the ribbon from time to time relative to the point of impact of the type bars, only a small percentage of the total inked surface of the ribbon may be utilized. Usually, this percentage 25 is only about 25% of the total area of the ribbon.

With these facts in mind the invention seeks to provide simple and efficient means 30 for shifting the path of the ribbon with respect to the point of impact of the type bars so that the entire surface of the ribbon may be utilized.

The invention consists in certain novel 35 and improved features of construction and combination of parts hereinafter fully described and illustrated in the accompanying drawings, in which

40 Figure 1 is a side elevation of my invention,

Figure 2 is a front elevation of the same,

Figure 3 is a fragmental detail view of one part of the sectional guide stem,

45 Figure 4 is a similar view of the other part of the sectional guide stem,

Figure 5 is a sectional view taken on the line 5-5 of Figure 2,

50 Figure 6 is an enlarged sectional view taken on the line 6-6 of Figure 2, parts thereof being broken away.

55 Referring more particularly to the accompanying drawings, wherein like reference numerals designate like parts throughout, the numeral 1 indicates the usual type bar guide employed in machines of this charac-

ter. The type guide 1 is rigidly secured to a fixed portion of the machine frame 2 and is provided with the usual V-shaped notch 3 at its upper end, said notch designed to receive and guide the type bars into proper position with the line of print. The type guide 1 is usually mounted a slight distance in front of the roller or printing platen (not shown) to provide a space in which to mount the usual ribbon guide in order that the ink ribbon may be made to pass between the type guide and the platen.

In the present construction any approved type of ribbon guide per se may be employed, such as shown at 4, but whereas such 70 ribbon guide is usually mounted upon a stem fixed as to length, the present invention contemplates a two-part or sectional stem comprising an upper or guide-carrying portion 5, and a lower or actuating portion 6. 75 The lower portion 6 may be connected to the operating mechanism of the machine (not shown) in the usual manner, to provide for elevating the ribbon guide from a point below the line of print to a point in coincidence therewith each time a type lever is actuated, in order to insure complete visibility of the line of print across the point at which the type bars engage the platen. This 80 construction is usual in all so-called "visible" 85 machines and forms no part of the present invention.

The ribbon guide stem sections 5 and 6 are preferably stamped from sheet metal, the lower section 6 being formed with a laterally 90 extending wing 7 provided with a rectangular window or aperture 8. The wing 7 is designed to be bent upon itself on the lines indicated at 9, 10 and 11, to form a rectangular frame or yoke 12, the aperture 8 of the 95 wing being so positioned therein that when the yoke 12 is formed said window or aperture will lie in the front face of the yoke, as clearly shown in Figure 2. The upper section 5 of the ribbon guide stem is similarly 100 formed with a wing 13 designed to be bent upon itself on lines 14, 15, and 16, to form a second yoke or frame 17, the yokes 12 and 17 being of such relative dimensions as to permit the yoke 17 to telescope within the yoke 12, as shown in Figure 5.

The yokes 12 and 17 are so formed with respect to the body portions of the stem sections 5 and 6 that when arranged in telescopic engagement, as shown in Figure 5, 110

the sectional stem portions 5 and 6 will overlie and coincide with each other, as clearly shown in Figures 1 and 2. In order to retain the stem sections 5 and 6 in such overlying relationship, the stem 6 is provided with overlying lugs 18 and 19, said lugs being formed integral with the stem 6, as shown in Figure 3. By thus forming the stem portions 5 and 6 with the yokes 12 and 17, and lugs 18 and 19, said stem sections may be assembled as shown in Figures 1 and 2, to form a complete ribbon guide and operating stem therefor with the yoke members telescopically engaged and surrounding the type bar guide member 1, while the stem portions 5 and 6 may be adjusted longitudinally with respect to each other in order to increase or diminish the overall length of the ribbon guide and stem for the purpose of shifting the path of the ribbon with respect to the point of impact of the type bars.

Novel means are provided for maintaining the stem sections in an adjusted position, said means including a sliding spring-pressed bolt member 20, and a cooperating rack 21, carried by the yoke members 17 and 12, respectively. As shown in Figure 4, the wing 13, from which the yoke or frame 17 is formed, is provided on that face which ultimately forms the front face of the yoke, with a pair of interior stampings 22. These stampings 22 are upset and inturned, as shown in Figure 6, to provide an open bolt-receiving channel 23. Within the channel 23 is mounted the bolt 20, said bolt being provided with a spring-receiving slot 24 extending therethrough from top to bottom and tapering narrowing toward the top. A coil spring 25 is housed within the slot, said spring, due to the tapered formation of the slot, being positively prevented from escaping therefrom. The front face of the yoke 17 is provided with an upstanding stud or pin 26, said pin extending through the slot 24 of the bolt, to provide an abutment against which one end of the coil spring 25 engages. By this construction it is apparent that the spring 25, confined in the slot of the bolt, and engaging the bolt and pin at its opposite extremities, tends to keep the bolt projected towards the left, as shown in Figure 2. A suitable operating knob 27 is provided at the end of the bolt for retracting the bolt against the tension of the spring when desired.

The rack 21, designed to cooperate with the bolt 20, is formed in one of the vertical edges of the aperture 8 of the yoke or frame 12, and is positioned relative to the bolt so that the latter, under the action of the spring 25, engages one of the teeth of the rack to maintain the two sections 5 and 6 of the ribbon guide stem in a predetermined adjusted position.

In the operation of my improved ribbon guide, when it is desired to change the path of the ribbon, the bolt 20 is retracted by the knob 27 against the tension of the spring 24 to withdraw the bolt from engagement with the teeth of the rack 21. The stem member 5 is then shifted up or down upon the stem section 6, one or more teeth, as desired, and the bolt then released to again engage a tooth of the rack to retain the parts in their adjusted position. The range of adjustment of the ribbon guide is determined by the vertical dimension of the aperture 8 in the yoke 12, and this is preferably made approximately equal to the width of the ink ribbon so that the ribbon may be shifted sufficiently to bring all portions thereof into line with the point of impact of the type bars.

From the foregoing description, taken in connection with the accompanying drawings, wherein I have illustrated a preferred embodiment of my invention, it will be seen that I have provided an adjustable ribbon guide for typewriting machines and the like which will permit the entire area of the ink ribbon to be utilized. It is to be understood, however, that the foregoing description and illustration are but for the purpose of example only and not as defining the limits of my invention which are to be determined from the scope of the appended claims.

Having thus described my invention, what I claim as new is:

1. A device of the character described comprising a ribbon guide, a sectional supporting stem therefor, the sections of said stem being telescopically arranged, one of said sections being apertured, the wall of said aperture being provided with a rack, a bolt member carried by the other section and being disposed within the aperture of the first section, and spring means urging said bolt into engagement with the rack to maintain the sections in an adjusted position.

2. The combination with a typewriting machine having a type bar guide, of a ribbon guide associated therewith, a sectional supporting stem for the ribbon guide, the sections of said stem being provided with telescopically engaged yoke members surrounding said type bar guide, and cooperative means carried by the yoke members for maintaining the sections in an adjusted position.

3. The combination with a typewriting machine having a type bar guide, of a ribbon guide associated therewith, a sectional supporting stem for the ribbon guide, the sections of said stem being provided with telescopically engaged yoke members surrounding said type bar guide, one of said yoke members being provided with an aperture having a serrated wall, the other of

said yoke members carrying a spring pressed bolt disposed within the aperture of said first mentioned yoke and engaging the serrations thereof to maintain the sections in an 5 adjusted position.

4. A device of the character described comprising a ribbon guide, a sectional supporting stem therefor, the sections of said stem being shiftable with respect to each 10 other to vary the length of the stem, one of said sections partly overlying the exposed forward face of the other section, said overlying portion being provided with a rack, and a bolt member carried by said other section 15 and engageable with the rack to retain the sections in an adjusted position, where-

by said adjustment may be accomplished from the exposed forward face of the stem.

5. A device of the character described comprising a ribbon guide, a sectional supporting stem therefor, the sections of said stem being arranged in superposed relation and shiftable with respect to each other to vary the length of the stem, one of said sections carrying a yoke member through which 25 the other section extends, said yoke being provided with a rack, and a bolt member carried by said other section and engageable with the rack to retain the section in an adjusted position. 30

In testimony whereof I affix my signature.
CALVIN I. KEPHART.
